TRANSMISSION MECHANISM

Joseph F. Joy, Pittsburgh, Pa., assignor to Sullivan Machinery Company, a corporation of Massachusetts

Application June 15, 1935, Serial No. 26,813
Renewed January 18, 1939

11 Claims. (Cl. 74—125.5)

My invention relates to transmission mechanisms, and more particularly to transmission mechanisms having load-limiting and speed-controlling features incident thereto.

5 The invention is particularly adaptable to the feeding mechanisms of coal-cutting machinery and to the operation of haulage devices, as will be apparent from the ensuing description. In the feeding of mining machinery, and particularly of the type which is movable over the mine bottom during cutting, it is necessary to provide powerful, tractive effort, but at the same time it is desirable to preclude the possibility of the exertion of excessive traction in order that excessive strains on the mechanisms, excessive loads on the motor, and breakage of the flexible feeding elements employed may be avoided. It is also desirable to provide a wide variation in feeding speed, that is to say in the winding speed of the 10 devices which cooperate with the flexible feeding elements used. My invention provides a definite maximum limit to the tractive effort which may be exerted and a wide range of cutting speeds from a predetermined, maximum, continuous 15 winding speed down to no winding at all, with substantially any intermediate winding rate desired, by determining the relative duration of alternate winding and idle periods.

An object of my invention is to provide an improved transmission mechanism. Another object of my invention is to provide an improved transmission mechanism having improved load-limiting features. A further object of my invention is to provide an improved transmission mechanism 20 having improved means therein for providing intermittent or continuous winding as desired. Still another object of my invention is to provide an improved transmission mechanism providing for a wide range of effective speeds by varying the alternate periods of motion and inactivity. Another object of my invention is to provide an improved load-limiting device for a transmission mechanism. Still another object of my invention 25 is to provide an improved load-limiting device having an invariable maximum and permitting speed variation through associated parts. Still another object of my invention is to provide an improved mining machine feeding mechanism. Other objects and advantages of the invention 30 will hereinafter more fully appear.

In the accompanying drawing, in which for purposes of illustration one embodiment of the invention is shown—

55 Fig. 1 is a view from above, with parts broken

away, showing a mining machine feeding mechanism in which the invention is incorporated,

Fig. 2 is a vertical section on the line 2—2 of Fig. 1,

Fig. 3 is a vertical transverse fragmentary section on the plane corresponding to the line 3—3 of Fig. 1,

Fig. 4 is a vertical section showing details of construction and taken on the plane of the line 4—4 of Fig. 1.

Referring to the drawing, it will be observed that a motor 1, provided with an armature shaft 2 carrying a driving pinion 3, drives, through an intermediate gear 4, a gear 5 which is keyed at 6 to a horizontal, longitudinally extending shaft 7. Said shaft 7 near its rearward end supports a worm 8 which meshes at its opposite sides with worm wheels 9 and 10 respectively. The worm wheel 10 is fixedly secured to a vertical shaft 11, which carries a worm 12 which engages and drives a worm wheel 13, suitably supported upon a transversely extending shaft 14 which is journaled in the frame of the apparatus at 15 and supports at its opposite ends winding elements 16 and 17, which may be connected thereto under the control of mechanism having an operating handle 18 as desired. The worm wheel 9 is connectible by a friction clutch 19, loaded as hereinafter described, to a vertical shaft 20 which carries a worm 21 engaging and driving a worm wheel 22, also supported upon the transverse shaft 14. The worm wheels 13 and 22 are connectible under the control of suitable ball clutches 23 and 24 operated by a shipper member 25, in driving relation with the shaft 14. 20 25 30 35

The structure so far described is substantially identical with the structure shown and described in my assignee's copending Holmes application Serial No. 699,024, now matured into Patent No. 2,091,985, dated Sept. 7, 1937.

40 Suitable means for loading the friction clutch 19 is provided for effecting intermittent or continuous loading of the clutch and for further providing a maximum load limit. This clutch loading apparatus includes a loading ring 30 having fingers 31 adapted to press the clutch discs together, and pressure is applicable to the loading ring through a second ring 32 supported by the ring 30 on antifriction bearings 33; and a clutch shipper member having arms 34 and supported by a transversely extending, hollow, oscillating shaft 35 is adapted to apply the pressure to the ring 32 to effect actual loading of the clutch. The shaft 35 is appropriately journaled on a transverse shaft 35a in the frame of the appara- 45 50 55

tus, and carries at its end nearer the worm 12 the upwardly extending arm structure 36 in approximately right-angular relation to the plane of the shipper arms 34. The arm structure 36 carries at its upper end a pair of wear plates 37 and 38, and is open between its sides, as at 39, and between its ends, to permit the projection through it of an adjustable support structure 40. This support structure comprises a rod-like portion 41 guided in a sleeve 42 carried by the frame and a forward bifurcated end 43 carrying a transverse pivot pin 44; and at its rearward end the support structure carries in fixed relation thereto a collar member 45 having a projecting lip portion 46 which projects into an annular groove 47 in a manually rotatable, adjusting member 48 which is threadedly supported at 49 upon the exterior of a load-limiting device 50 which will be described in detail shortly. The pivot 44 supports a lever member 51 whose forward extremity 52 is adapted to coact with a multi-lobed cam 53 secured to the hub 54 of the worm wheel 13. The member 51 has a projecting portion 55 which is adapted to engage the wear plate 38 carried by the upper end of the relatively vertical arm 36.

The load-limiting device 50 comprises a sleeve-like body portion 57 having a bore 58 in which a spring 59 is enclosed, said spring at its rearward end engaging a closure element 60 and at its forward end engaging the collar portion 61 of an internal rod member 62 whose forward end ends in a nose-like portion 63 which projects through an opening 64 in the front end of the sleeve member 57. It will be evident that the collar 61 will be limited in its forward projection by engagement with the shoulder 65, and accordingly that the spring 59 may be placed under any predetermined tension desired by the adjustment of the closure member 60, and thereafter the member 60 may be welded in position to preclude altering of the maximum compression of the spring. The sleeve member 57 carries an external shoulder 66, by means of which it is secured by bolts 67 to the frame of the machine. The nose 63 is adapted to engage the wear plate 37.

The mode of operation of the apparatus will be readily understood from what has been said. It will be obvious that so long as the motor drive pinion 3 is rotated the worm wheel 13 will be rotated and, accordingly, the cam 53 will be rotated. Fast feed drive of the transverse shaft 14 can be effected by shifting the shipper member 25 toward the worm wheel 13 in Fig. 1, under which circumstances the drive will be as follows: Motor pinion 3, idler 4, gear 5, shaft 7, worm 8, worm wheel 10, worm 12, worm gear 13, shaft 14, and either winding element 16 or 17 desired. When maximum slow speed is desired, the manually rotatable member 48 will be turned in a proper direction to cause the pivot pin 44 to move as far to the left as possible. This will have two effects. It will cause the end 52 of the arm member 51 to move beyond the vertical plane including the axis of the cam 53 and thereby reduce the raising and lowering movement of the arm 51, and will also move the portion 55 of the arm 51 bodily toward the left and allow the spring 59 to force the nose 63 toward the left, and thereby, through the pressure of the nose 63 upon the wear plate 37, cause the arm 36 to swing the shaft 35 and with it the clutch shipper 34 continuously into clutch-loading relation. At this time the spring 59 will be under somewhat greater compression than would be the case were the collar 61 against the shoulder 65, but in the design

of the machine the amount of this increase may be predetermined and the sealing of the spring in its container when under a fixed pressure will automatically effect an absolute control of the maximum load which can be applied to the 5 clutch.

In order to diminish the absolute rate of rotation of the shaft 14, the member 41 may be moved toward the right in Fig. 4 by rotation of the handle member 48, and as the pivot pin 44 is 10 moved toward the right the end 52 is moved bodily toward the right and engagement of the portion 55 with the wear plate 38 takes place for increasingly substantial periods, the further to the right the member 41 is moved. When the 15 member 41 is in extreme right-hand position the application of the load to the clutch 19 may be completely interrupted, or made any minimum desired, depending upon the range of adjustment of the member 41 permitted. In practice it is 20 customary to provide a range of adjustment such that the portion 55 may engage the wear plate continuously and force the arm 36 at all times, even when the portion 52 is in the troughs of the cam 53, to such a position that the shipper mem- 25 ber 34 can not load the clutch 19.

From the foregoing description it will be evident that the apparatus disclosed provides a continuous fast speed drive, and a slow speed drive varying from a certain maximum, uniform rate 30 of rotation, at which rate a maximum tension can be transmitted to the feeding elements, down, by reason of the interruptions of drive for varying periods, to a state of complete interruption 35 of drive. At all times the pressure which may be applied to the friction clutch 19 is completely limited, and, without actually deliberately breaking open the spring container, the operator is unable to take any action which might result in an overload of the motor, or breaking the ropes 40 or other flexible feeding elements; and moreover there is always insured an adequate pressure to be applied to the clutch discs to insure effective clutch engagement with a minimum wear due to slippage.

While there is in this application specifically described one form which the invention may assume in practice, it will be understood that this form of the same is shown for purposes of illustration and that the invention may be modified 50 and embodied in various other forms without departing from its spirit or the scope of the appended claims.

What I claim as new and desire to secure by Letters Patent is:

1. In combination, a driving member, a driven member, a friction clutch operative when loaded to connect said members for coaxial equiangular rotation, a lever swingable about a stationary pivot to load said clutch, yieldable means having a fixed point of reaction for applying loading pressure to said lever whereby the clutch is loaded by said yieldable means through said lever, said yieldable means having a predeterminedly-limited maximum pressure application, a continuously rotated cam, a lever pivotally movable thereby and having a portion effective on predetermined movements thereof to force said first mentioned lever against the pressure of said yieldable means into clutch unloading position, and means for altering the fulcrum point of said second mentioned lever to vary its action on said first mentioned lever and thereby the duration of loading of said clutch by said first mentioned lever.

2. In combination, a driving member, a driven member, a friction clutch operative when loaded to connect said members for coaxial equiangular rotation, a lever swingable about a stationary pivot to load said clutch, yieldable means having a fixed point of reaction for applying loading pressure to said lever whereby the clutch is loaded by said yieldable means through said lever, said yieldable means having a predeterminedly-limited maximum pressure application, a continuously rotated cam turning at an angular rate substantially less than the rate of rotation of said driving member, a lever pivotally movable thereby and having a portion effective on predetermined movements thereof to force said first mentioned lever against the pressure of said yieldable means into clutch unloading position, and means for altering the fulcrum point of said second mentioned lever to vary its action on said first mentioned lever and thereby the duration of loading of said clutch by said first mentioned lever.

3. In a transmission mechanism, a driving member, a driven member, a friction clutch for connecting said members in driving relation, yieldable means set at a predetermined pressure for applying said clutch under a predetermined load, means associated with said clutch applying means for releasing said clutch against the action of said yieldable clutch applying means at predetermined timed intervals including a cam continuously rotatable during drive of said driving member and a lever actuated by said cam and engaging said clutch applying means at a point intermediate its fulcrum and its cam-engaging-end, and means associated with said last mentioned means for varying said timed intervals of clutch release including means for varying the fulcrum point of said lever.

4. In a transmission mechanism, a driving member, a driven member, a friction clutch for connecting said members in driving relation, means for yieldably applying said clutch under a predetermined load including clutch actuating means and a coil spring acting on said clutch actuating means, and means for releasing said clutch against the action of said yieldable means at predetermined timed intervals including a cam continuously rotatable during drive of said driving member, a lever actuated by said cam and engaging said clutch actuating means at a point intermediate its fulcrum and its cam-engaging-end, and means associated with said last mentioned means for varying the time intervals of clutch release including means for adjusting the fulcrum point of said lever.

5. In an intermittent unidirectional transmission mechanism, a driving element, a driven element, a friction clutch for connecting said elements in driving relation, and means for variably intermittently applying and releasing said clutch at timed intervals to effect variable intermittent unidirectional drive of said driven member including a continuously rotating cam, yieldable clutch loading means always tending to load said clutch including a clutch loading spring set at a predetermined maximum clutch loading pressure, said clutch loading means further comprising a movably mounted member on which said spring acts whereby the clutch is loaded by the spring through said movably mounted member, a member movable relative to said movably mounted member and actuated by said cam for moving said movably mounted member into clutch releasing position against the action of said spring,

and means to vary the range of movement of said cam actuated member by said cam to vary the range of movement of said movably mounted member upon which said spring acts.

6. In an intermittent unidirectional transmission mechanism, a driving element, a driven element, a friction clutch for connecting said elements in driving relation, and means for variably intermittently applying and releasing said clutch at timed intervals to effect variable intermittent unidirectional drive of said driven member including a continuously rotating cam, yieldable clutch loading means always tending to load said clutch including a clutch loading spring set at a predetermined maximum clutch loading pressure, said clutch loading means further including a pivoted member, and said spring acting on said pivoted member at the end thereof remote from its pivot whereby the clutch is loaded by the spring through said pivoted member, a lever actuated by said cam for intermittently moving said pivoted clutch loading member into clutch releasing position against the action of said spring, said lever having an adjustable fulcrum and engaging said pivoted member at a point between its own fulcrum and its own engagement with said cam, and means for adjusting the fulcrum of said lever to vary the time intervals of clutch application and release.

7. In a transmission mechanism, coaxial relatively rotatable driving and driven members, a clutch for connecting said driven member to said driving member including cooperating clutch elements respectively rotatable with said driving and driven members, one clutch element movable along the axial line of said driving and driven members into driving engagement with said other clutch element, a lever for moving said axially movable clutch element into driving engagement with said other clutch element, a clutch loading spring directly acting on said lever at a point spaced from the clutch-engaging-end of the latter, said spring set at a predetermined clutch loading pressure for yieldingly moving said lever into its clutch loading position whereby the clutch is loaded by said spring through said lever, means engaging said lever in opposition to said spring for automatically swinging the lever against the pressure exerted by said spring for intermittently releasing said axially movable clutch element from driving engagement with said other clutch element at predetermined time intervals, and means associated with said last mentioned means for varying the time intervals of clutch release.

8. In a transmission mechanism, coaxial relatively rotatable driving and driven members, a clutch for connecting said driven member to said driving member including cooperating clutch elements respectively rotatable with said driving and driven members, one clutch element movable along the axial line of said driving and driven members into driving engagement with said other clutch element, a lever for moving said axially movable clutch element into driving engagement with said other clutch element, a clutch loading spring acting directly on said lever at a point spaced from its clutch-engaging-end and set at a predetermined clutch loading pressure for yieldingly moving said lever into its clutch loading position whereby the clutch is loaded by said spring through said lever, means engaging said lever in opposition to said spring for automatically swinging the lever against the pressure exerted by said spring for intermittently releasing said axially movable clutch element

from driving engagement with said other clutch element at predetermined time intervals including a rotatable cam and a lever actuated by said cam and operative to actuate said clutch applying lever.

5. In a transmission mechanism, a drive clutch, a clutch applying lever, a spring acting on said lever and set at a predetermined clutch loading pressure for urging said lever toward clutch loading position whereby the clutch is loaded by the spring through said lever, means connected to said lever for swinging the latter against the pressure exerted by said spring for intermittently releasing said clutch at timed intervals including a rotatable cam and a lever actuated by said cam and engaging said clutch applying lever in opposition to said spring, and means for varying the time intervals of clutch release including means for adjusting the fulcrum point of said second mentioned lever.

10. In a transmission mechanism, a drive clutch, a clutch applying lever, a spring acting on said lever and set at a predetermined clutch loading pressure for urging said lever toward clutch loading position whereby the clutch is loaded by the spring through said lever, means connected to said lever for swinging the latter

20. In a transmission mechanism, a drive clutch, a clutch applying lever, a spring acting on said lever and set at a predetermined clutch loading pressure for urging said lever toward

25. clutch loading position whereby the clutch is loaded by the spring through said lever, means connected to said lever for swinging the latter

against the pressure exerted by said spring for intermittently releasing said clutch at timed intervals including a rotatable cam and a lever actuated by said cam and engaging said clutch applying lever in opposition to said spring, and means for varying the time intervals of clutch release including means for adjusting the fulcrum point of said second mentioned lever, said fulcrum point adjusting means comprising an adjustable support to which said second mentioned lever is pivotally connected and means for adjusting said support.

11. In a transmission mechanism, a drive clutch, a clutch applying lever, a spring acting on said lever for yieldingly urging the latter into clutch loading position whereby the clutch is loaded by the spring through said lever, means acting against the pressure exerted by said spring for automatically swinging said lever intermittently to relieve the load on said clutch at predetermined timed intervals including a continuously rotating cam and a lever actuated by said cam and engaging said first mentioned lever in opposition to said spring, and means for adjusting the fulcrum point of said second mentioned lever to vary the time intervals of clutch release.

JOSEPH F. JOY.
